[57] **CLAIM**

The ornamental design for a pocket size maze game box, substantially as shown and described.

DESCRIPTION

FIG. 1 is an isometric view showing the top, the left side and one end of a pocket size maze game box showing my new design;

FIG. 2 is an end elevational view of the end not shown in FIG. 1;

FIG. 3 is a side elevational view of the side not shown in FIG. 1; and

FIG. 4 is a bottom plan view of the toy maze game shown in FIG. 1.
